UNITED STATES PATENT OFFICE.

DANIEL E. SALVUCCI, OF PHILADELPHIA, PENNSYLVANIA.

BOX WITH OPENING DEVICE.

Application filed January 14, 1924. Serial No. 685,940.

To all whom it may concern:

Be it known that I, DANIEL E. SALVUCCI, a citizen of the United States, residing at Philadelphia, in the county of Philadelphia and State of Pennsylvania, have invented a new and useful Improvement in Boxes with Opening Devices, of which the following is a specification.

This invention relates to a box provided with means for opening the same easily and conveniently and more particularly to a box having such means intended for marketing shoe polishing paste or similar material.

It is the object of this invention to provide a box of this character which permits of readily opening the same with facility and still permits of maintaining an air tight joint between the body and cover of the box when the goods are not in use and thus prevent the same from drying out; also to so design and arrange the parts of the opening device that the box can be stowed compactly for shipping and storage purposes and can be made without undue cost.

In the accompanying drawings:

Figure 1 is a side elevation of a sheet metal box adapted to packing shoe polish paste and equipped with my improved opening device, showing the members of the box in their fully closed position. Figure 2 is a similar view showing the box members partly separated by the use of the opener containing my invention. Figure 3 is a horizontal section taken on line 3—3, Figure 2. Figure 4 is a side elevation of the presser button forming part of the opening device. Figure 5 is an inside elevation of the same. Figure 6 is a fragmentary vertical section, on an enlarged scale, taken on line 6—6, Figure 3, and showing the parts corresponding to the position shown in Figure 2.

Similar characters of reference refer to like parts in the several views.

The box shown in the drawings as an example of one suitable for receiving my invention has its body and cover members constructed of sheet metal similar to those now commonly used for packing shoe polish paste. In this case the body of the box has a bottom 10, a cylindrical side wall or flange 11 rising from the edge of the bottom and an annular head or rib 12 projecting laterally from the wall 11 at a short distance below the upper edge of the same, this bottom wall and bead being preferably con-

structed integrally from a sheet of tin in a well-known manner.

The cover is similarly constructed of a single piece of tin so as to form a top 13, a cylindrical side wall or flange 15 depending from the edge of the top, and an annular bead or rib 16 projecting laterally from the wall of the cover a short distance above the lower edge of the same. As usual the wall or flange of the cover slip over the upper edge portion of the wall or flange of the body with a friction tight fit so as to prevent leakage of air into the interior of the box when the same is closed and avoid drying out or impairing the quality of the contents packed therein.

My improved opening device which cooperates with these box members for partly separating or loosening them so that their complete detachment can be effected without any difficulty is constructed as follows:

Movable radially toward and from the adjacent parts of the body and cover when the same are assembled is a push button which is preferably constructed from a single piece 80 of metal or other suitable material and which comprises an outer upright finger piece 14 adapted to extend vertically across the beads of the body and cover, a wedge 17 projecting inwardly from the finger piece 85 about midway of its height and adapted to engage with the opposing sides of the beads on the body and cover, and a stop lug 18 projecting inwardly from the upper end of the finger piece and adapted to engage with 90 the upper side of the bead on the cover. This finger piece may be movably supported on one of the box members in any suitable or approved manner, the means for this purpose shown in the drawings is an example which is satisfactory and consisting of a supporting band, loop or hoop 19 of flexible or pliable wire which encircles or embraces that part of the cover wall or flange below its bead and has a floating part 100 of bow shape which is attached to the push button and a fixed part which is attached to the wall of the cover. The fixed part of the supporting band is preferably connected with the wall of the cover by soldering the 105 same thereto at a suitable number of places, as shown at 20, and the floating part of the same is connected with the push button by splitting the wedge thereof, as shown at 21, and securing the central part of the bow 110

or floating portion of this band between the parts of the wedge formed by said split, the connection between the wedge and the supporting band being effected either by pressing the wedge sections so as to pinch or grip the wire therebetween, or by soldering or welding the same together.

Normally, when the box is fully closed and no pressure is applied to the push button the latter is moved laterally into its outermost position, as shown in Figure 1, whereby the wedge is withdrawn to such an extent that the body and cover of the box can be pressed together the maximum extent for tightly sealing the same and the adjacent parts of their beads come closely together. For the purpose of loosening the cover and body relatively to each other and partly opening the box, this is accomplished by pushing the button inwardly toward the box whereby the wedge engages its inclined surfaces with the opposing sides of the beads on the body and cover and forces the same apart to such an extent as to permit the complete separation of these box members to be effected without difficulty if access to the material within the box is desired. Upon releasing the inward pressure on the push button, the resilience of the wire band moves the push button outwardly automatically so that the wedge is withdrawn from between the beads to such an extent as will permit of pressing the cover and body fully together for closing the box and protecting its contents against deterioration.

If, in addition to a radial inward pressure, a vertical pressure should be applied to the push button during the operation of loosening the body and cover and opening the box, such vertical movement is prevented by reason of the wedge engaging with the underside of the cover bead which resists upward movement of the push button and the stop lug of the push button engaging with the upper side of said bead and resisting downward movement of the push button, thereby preventing displacement of the latter with reference to the cover and avoiding breaking or injuring the supporting band which otherwise might be liable to occur.

This box opener is not only very simple and inexpensive in construction and capable

of being readily applied to the standard forms of boxes now in use, but the same is also very efficient in operation inasmuch as it permits of easily and quickly loosening and opening the box, and it also is compact in construction so that the same will not occupy any more room when packed for storage or transportation than a box of ordinary construction.

I claim as my invention:

1. A box comprising a body member having a lateral projection, a cover member engaging with said body and provided with a lateral projection, a finger piece movable toward and from said box members, a split wedge arranged on said finger piece and adapted to engage with the opposing sides of said projections, and means for movably supporting said finger piece and wedge on one of said box members.

2. A box comprising a body member having a lateral projection, a cover member engaging with said body and provided with a lateral projection, a wedge adapted to engage with the opposing sides of said projections, and a flexible wire bow having a floating part which is connected with said wedge and fixed parts which are attached to one of said box members on opposite sides of said wedge.

3. A box comprising a body having an upwardly projecting side wall and a circumferential bead projecting laterally from said wall, a cover having a downwardly projecting wall which is adapted to slip over the wall of the body and provided with a circumferential bead projecting laterally from the respective wall, a finger piece movable toward and from the walls of said body and cover, a wedge arranged on the central part of the inner side of said finger piece and adapted to engage with the opposing sides of said beads, a stop projecting inwardly from the upper end of said finger piece and adapted to engage with the upper side of the bead on the wall of the cover, and a flexible wire bow which embraces the wall of the cover below the bead thereof and has its central part connected with said wedge while its side parts are connected with the cover wall below the bead thereof.

In testimony whereof I affix my signature.
DANIEL E. SALVUCCI.
